UNITED STATES PATENT OFFICE.

LOUIS HILL, OF AKRON, OHIO.

SAFETY APPARATUS FOR GAS ILLUMINATING DEVICES.

Application filed October 23, 1923. Serial No. 670,230.

My invention relates to a safety apparatus for gas illuminating devices, of the type in which a gas burner is controllable by hand for the purpose of turning on and off the flow of gas, and in which means are provided for automatically turning off the flow of gas in the event that the gas flame is at any time extinguished when the flow of gas is not turned off by hand.

More particularly stated, I seek to produce a device of the general character just mentioned and having but few mechanical parts, these parts being of simple construction and each having such form as to enable it to be made up cheaply and readily standardized, my device as a whole being suitable for burners of the kind that have already come into general use.

Reference is made to the accompanying drawing forming a part of my specification, and in which like reference characters indicate like parts throughout the several figures.

Figure 1 is a substantially central vertical section through an illuminating gas burner of ordinary construction, provided with my improved apparatus.

Figure 2 is a side elevation of the mechanism appearing in Figure 1 with the exception that the globe is missing.

Figure 3 is a plan view of the mechanism appearing in Figure 2.

Figure 4 is a plan view of a star wheel forming a part of my device.

A gas valve appears at 5, and is provided with a valve plug 6 held in position by aid of a cotter pin 7, and is of the usual or any desired construction.

Secured rigidly upon the valve plug 6 and extending upwardly therefrom is an arm 8, used as hereinafter described.

The body portion of the burner appears at 9, and extending upwardly from it is a burner tube 10, provided with a rather massive cylindrical portion 11. This portion is encircled by a groove 12, and fitting into this groove is a wheel 13, provided with notches 14, as indicated in Figure 4, and which I designate as a star wheel.

A mantle 15, supported by the burner tube 10, extends upwardly therefrom as indicated in Figure 1. Within the base of the mantle 15 the burner tube is provided with a reticulated dome 16.

Encircling the burner tube 10 and carried thereby is a floor 17, integral therewith

and provided with an upwardly extending flange 18 of annular form. A globe is shown at 19 and is fitted into the flange 18, so as to rest upon the floor 17.

The floor 17 is provided with an opening 20 of small size, and is further provided, adjacent this opening, with a lug 21, serving as a bearing.

Pivotedly mounted upon the bearing 21 and loosely extending through the opening 20 is a locking lever 22. The upper end of this lever is provided with a slot 23.

A thermostatic bar 24 is provided with an end portion 24^a which extends through the slot 23, as may be understood from Figures 1 and 3. The connection thus made, between the locking lever 22 and the thermostatic bar 24, is somewhat in the nature of a spring pivot. That is, the end portion 24^a, extending through the slot 23, acts to some extent as a torsion spring and thus permits a slight torsional movement to take place between the locking lever 22 and the thermostatic bar 24, as indicated by full and dotted lines in Figure 1.

Whenever the thermostatic bar is heated or cooled, as hereinafter described, a corresponding torsional movement takes place as indicated by the full and dotted lines shown in Figure 1 as just described.

The thermostatic bar is provided with an end portion 25, bent as indicated in Figure 1 and secured to the annular floor 17 by a rivet 26, as indicated in this figure.

A tensile spring 27, shown in Figure 2, is connected at one of its ends with the arm 8 and at its other end with a stationary lug 28, so that the spring 27 is always under tension and has a tendency to rock the arm 8 in a counter-clockwise direction according to Figure 2, and thus always has a tendency to shift various parts, directly controllable by the spring, into the positions indicated for them by dotted lines in this figure.

Integral with the arm 8 is a chain arm 29, these two arms together constituting a bell crank lever. The chain arm 29 is provided with an eye 30 for facilitating its connection with a rod 31, through the medium of which the bell crank lever is actuated by hand.

The thermostatic bar 24 and the locking lever 22 are formed and arranged as illustrated. These two parts have together, when cold, the form of a symmetrical bow as indicated by full lines in Figure 1, but when the thermostatic bar is heated, the parts just

mentioned assume the form of a distorted or broken bow, as indicated by dotted lines in Figure 1.

The operator, by pulling or pushing upon the rod 31, can always cause the star wheel 13 to rock, and thus can at will turn the gas on or off. If this movement takes place while the thermostatic bar 24 is hot, so that the lower end of the lever 22 extends into some one of the notches 14, this does not prevent the star wheel from being rocked, as the lower end of the lever 22 is merely moved out of one notch, and automatically back into another.

It will be noted that the thermostatic bar is bent partially around the mantle 15, so that when the gas is burning the thermostatic bar is in close proximity to the burner flame. Therefore the thermostatic bar will remain heated so long as the gas continues to burn, and during this time the lower end of the locking lever 22 will always rest in some one of the notches 14, so as to keep the star wheel 13 locked, and thus by preventing the arm 8 from being moved by tension of the spring 27, will maintain the valve plug 6 in the position indicated for it in Figure 1. In the event, however, of the gas flame being extinguished by a gust of wind or in any other such manner so as to leave the unburned gas flowing through the burner, the cooling of the thermostatic bar 24 causes this bar and the locking lever 22 to assume the positions indicated for them by full lines in Figure 1. The locking lever 22 is thus moved out of engagement with the star wheel 13, and the latter, being thus unlocked, is now free to turn; and the arm 8, under control of the tensile spring 27, is thereupon rocked, in a counter-clockwise direction according to Figure 2, so as to rock the valve plug 6 and thus close the valve.

The operation of my device may readily be understood from the foregoing description.

Suppose that at the start the valve is closed, so that the arm 8 and parts controllable thereby occupy the positions indicated for them by dotted lines in Figure 2, and that the operator wishes to light the gas.

By pulling upon rod 31 he causes the arm 8 to move into the position indicated for it by full lines in Figure 2, thus extending the tensile spring 27 and opening the valve, as indicated in Figure 1. The gas now begins to flow through the mantle and is easily lighted by hand. The operator continues to pull upon the rod 31 for a moment after the gas is lighted, so as to allow the thermostatic bar 24 to become heated and thus to expand. This done, the operator releases the chain 31. The locking lever 22, by preventing the star wheel from turning, prevents the arm 8 from being rocked by the spring 27 and thus prevents the valve from closing.

Suppose, next, that the gas flame is extinguished while the gas is still flowing, as for instance by a gust of wind. The consequent cooling of the thermostatic bar causes this bar and the locking lever 22 to assume the positions indicated for them by full lines in Figure 1. The locking lever 22 therefore releases the star wheel 13, and thereupon the contraction of the spring 27 causes the valve to close.

The automatic action of the burner does not prevent the operator from opening and closing the valve by hand, by pushing and pulling the rod 31 as above described.

I do not limit myself to the particular mechanism here shown and described, as variations may be made without departing from my invention, the scope of which is commensurate with my claims.

I claim:

1. In a device of the character described the combination with a gas burner and a valve for controlling the flow of gas thereto, of a lever connected with said valve in order to enable said valve to be actuated, a spring connected with said lever and having a tendency to turn said lever into position to close said valve, a star wheel revolvably mounted upon said burner and provided with teeth for restraining said lever against the tension of said spring, a locking lever provided with a portion for engaging said teeth of said wheel to prevent rotation of said star wheel, and a thermostatic bar connected with said locking lever for actuating said locking lever, said thermostatic bar being located in close proximity to said burner and thus adapted to be heated thereby.

2. In an apparatus of the character described the combination, with a gas burner and a valve for controlling a supply of gas thereto, of an arm connected with said valve for opening and closing the same, a spring connected with said arm for the purpose of actuating said arm and thus closing said valve, a star wheel revolvably mounted upon said burner and having a plurality of separate notches into which said arm can be fitted for holding said star wheel in different positions in order to prevent movement of said arm from closing said valve, a locking lever journaled in close proximity to said star wheel and having a portion movable into and out of said notches in order to enable said locking lever to release said star wheel, and thermostatic mechanism connected with said locking lever for the purpose of actuating the same, said thermostatic mechanism being located in proximity of said burner and controllable by the heat thereof.

3. In a device of the character described the combination, with a gas burner and a valve for controlling the flow of gas thereto,

of an arm connected to said valve and movable for controlling the same, a spring connected with said arm for shifting the position thereof in order to close said valve, a 5 revolute member mounted upon said burner and revolute relatively thereto, said revolute member being provided with a portion for engaging said lever in order to prevent said lever by its movement from closing 10 said valve, said revolute member being provided with notches, a locking lever journaled upon said burner and provided with a portion for extending into said notches in order to prevent the movement of said revolute 15 member, and a thermostatic bar connected with said locking lever for the purpose of shifting the same into different positions depending upon the temperature of said thermostatic bar, said thermostatic bar being 20 located in close proximity to said burner and heated thereby.

4. In a device of the character described the combination, with a gas burner and a valve for controlling the flow of gas thereto, 25 of mechanism for closing said valve, a locking lever connected with said mechanism for temporarily restraining the same and thus preventing said mechanism for the time being from closing said valve, a pivot upon 30 which said locking lever is mounted in order

to enable it to rock, and a thermostatic bar connected with said locking lever by means of a spring pivot, so that said thermostatic bar and said locking lever comprise practically a single continuous member, said 35 thermostatic bar being located in proximity to said burner in order to be heated thereby.

5. In a device of the character described the combination with a gas burner and a valve for controlling the supply of gas thereto, 40 of mechanism for closing said valve, a locking lever journaled upon said gas burner and movable into a predetermined normal position for the purpose of restraining said mechanism and thus preventing it from closing said valve, said locking lever being provided with a slot, and a thermostatic bar provided with an end portion extending through said slot and thus forming a spring pivot connecting said thermostatic bar with 45 said locking lever in order to enable movements of said thermostatic bar to actuate said locking lever, said thermostatic bar being located in close proximity to said burner and heated thereby.

Signed at Akron, in the county of Summit and State of Ohio, this 19th day of October, 1923.

LOUIS HILL.
